UNITED STATES PATENT OFFICE.

EDWIN O. PRESBY, OF NEW YORK, N. Y.

BUTTON.

1,137,789.

Specification of Letters Patent. Patented May 4, 1915.

Application filed May 7, 1914. Serial No. 836,971.

To all whom it may concern:

Be it known that I, EDWIN O. PRESBY, a citizen of the United States, residing at New York, in the county of New York and State 5 of New York, have invented certain new and useful Improvements in Buttons; and I do hereby declare the following to be a full, clear, and exact description of the invention, such as will enable others skilled in the art 10 to which it appertains to make and use the same.

The present invention relates to buttons especially for use with lacings, and has for its purpose to provide a button of that type 15 having a rigid stud or shank and which may be readily attached to the ordinary lacing eyelet openings to receive the lacing, and which will hold the same in an effective manner and readily allow of unlacing.

20 A further purpose of the invention is to provide a button substitute for eyelet lacings to the end that shoes having the latter style of fastening may be readily changed to the other and with very little trouble and 25 expense.

With these and other objects in view the invention consists in the novel details of construction and combinations of parts more fully hereinafter disclosed and particularly 30 pointed out in the claims.

In the accompanying drawings forming a part of this application, and in which similar reference symbols indicate corresponding parts in the several views: Figure 1 35 illustrates the application of the invention to a shoe. Fig. 2 is a central vertical sectional view of the button and showing its several parts and manner of assembly. Fig. 3 is a perspective view of the several members of the button in disassembled relation. Fig. 4 is a modified construction of one of 40 the parts.

Referring to the construction in further detail, the button consists of a tubular member 1 having a flange 2 and a reduced portion 3 at its respective ends. A base member 4 having a base piece 5 and a tubular shank 6 passes through the tubular member 1, as in the manner shown in Fig. 2, and said 45 tubular shank 6 is constructed with a reduced portion 7 forming an annular shoulder 8, and said portion 7 is split, as at 9, whereby to give the necessary resiliency for 50 passing through the reduced end 3 of the member 1 and forming a close fit therewith. The tubular member 1 and base member 4

tightly fit within the opening of the eyelet 10 that is secured to the shoe upper 11, through the medium of flanged edges 12 or in any other approved manner. The annular shoulder 8 of the member 4 engages with the inner end 13 of the member 1, and serves to hold said members 1 and 4 in proper relative axial relation, as illustrated in Fig. 2. 65

The button *per se* comprises a rounded head 14 having an integrally formed and rigid shank 15 that has an enlarged and split end 16. The shank 15 is adapted to pass through the tubular shank of the base member 4 and be secured thereto by upsetting the end 16, as will be obvious. To upset said end a block or mandrel 16^a is provided, and is formed with a cavity or recess 17^a to receive the shank end 16 and cause the latter to be 75 blunted or upset in the manner of riveting. The head 14 fits over and completely incloses the flanged end 2 of the tubular member 1; and the shank 15 has a relatively close fit with the shank portion 7, and together with 80 the reduced portion 3 of the tubular member 1, the several parts afford a substantial and rigid shank for the button, and hold the same in a position well suited to receive the shoe lacing A and with the ordinary tension 85 to which the latter is subjected.

In the arrangement shown in Fig. 4, the base piece 5^a is elongated and of less width than the corresponding part 5 in the other structure, but in all other respects this part 90 of the button is the same as that above described. The object in having the base piece elongated (viz. 5^a) is to provide an elongated supporting surface for the button shank in order to avoid liability of tilting of the 95 shank when the laces are drawn.

The button as disclosed herein, while adapted for use in most any form of eyelet where lacing is used, is especially adapted for use on shoes, as illustrated in Fig. 1. 100 As previously set forth this arrangement allows of an outside lacing to be applied to shoes which are constructed with eyelets.

It is obvious that those skilled in the art may vary the details of construction and 105 arrangement of parts without departing from the spirit of my invention, and therefore I do not wish to be limited to such features except as may be required by the claims.

I claim:

1. A lacing button for shoes comprising

a tubular member; a base member having a tubular shank and an annular shoulder, adapted to pass through said tubular member, and to engage said tubular member; 5 and a head having a rigid shank adapted to pass through said tubular shank and to be secured thereto by upsetting, substantially as described.

2. A lacing button for shoes comprising a 10 tubular member; a base member having a tubular shank adapted to pass through said tubular member; and a head having a rigid shank adapted to pass through said tubular shank, said shank having an enlarged and 15 split head adapted to be upset against said base member whereby to secure the several parts, substantially as described.

3. A lacing button for shoes comprising a 20 tubular member having a reduced end portion; a base member having a tubular shank, said shank having a reduced portion adapted to pass through and to form a close fit with 25 said reduced tubular portion; and a head

having a rigid shank adapted to pass through and to form a close fit with said 25 tubular shank and to be secured thereto by upsetting, substantially as described.

4. A lacing button for shoes comprising a 30 tubular member formed with a flange and having a reduced end portion; a base member having a tubular shank, said shank having a reduced portion adapted to pass through and to form a close fit with said 35 reduced tubular portion; and a head having a rigid shank adapted to pass through and to form a close fit with said tubular shank and to be secured thereto by upsetting, and said head being adapted to engage the flange 40 of said base member, substantially as described.

In testimony whereof, I affix my signature, in presence of two witnesses.

EDWIN O. PRESBY.
